UNITED STATES PATENT OFFICE.

JOHN H. HAMILTON, OF BROCKTON, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

MACHINE FOR WORKING UPPERS OVER LASTS.

1,358,149.

Specification of Letters Patent.

Patented Nov. 9, 1920.

Application filed July 3, 1916. Serial No. 107,365.

To all whom it may concern:

Be it known that I, JOHN H. HAMILTON, a citizen of the United States, residing at Brockton, in the county of Plymouth and 5 State of Massachusetts, have invented certain Improvements in Machines for Working Uppers Over Lasts, of which the following description, in connection with the accompanying drawings, is a specification, 10 like reference characters on the drawings indicating like parts in the several figures.

This invention relates to machines for working uppers over lasts and is shown by way of illustration as embodied in a lasting 15 machine of the hand method type, such, for example, as that shown in United States Letters Patent No. 597,321, granted January 11, 1898, on application of Sherman W. Ladd, and especially to such machines when 20 adapted for lasting the sides of welt shoes. It is to be understood, however, that the invention is not limited in its application to machines of the above-mentioned type.

In lasting welt shoes, except at the heel 25 seat where they are completely driven, the tacks are left upstanding to facilitate pulling them out after they have served their purpose, and frequently the tacks are driven in a direction inclined downwardly 30 and inwardly toward the middle line of the last. In lasting the shanks of shoes on lasts which are deeply undercut at the shank, as are most modern lasts, particularly in women's shoes, to provide a narrow shank, 35 it is necessary to tilt the shoe so that the normal inclination of the tack relatively to the shoe bottom is increased to such an extent that frequently the upper slips upwardly toward the head of the tack and 40 therefore becomes slack. To overcome this difficulty it has been proposed, as in United States Letters Patent No. 1,109,700, granted September 8, 1914, on application of Thomas N. O'Brien, to bend the tack inwardly 45 by means projecting from the wiper which works the upper over the last bottom and adapted to contact with and bend inwardly a previously driven tack when the wiper moves over the shoe bottom to drive 50 the following tack.

In the operation of the machine of this prior patent it is necessary for the operator to hold the shoe against the thrust of the advancing wiper to insure bending of

the previously driven tack before the following tack is driven. If the operator neglects to hold the shoe firmly it is apt to be pushed toward him and away from the machine with the result that the following tack is improperly located with respect to 55 the edge of the shoe bottom.

An object of this invention is to provide an improved tack bending mechanism and one which will bend a tack in the same cycle of the machine in which the tack is driven, 60 the tack driving and tack bending operations being completed in one cycle and independently of the preceding or following cycles of the machine.

A feature of the invention consists in 70 means which acts upon the tack immediately after it is driven to bend the tack. As shown herein, a tack bender is provided which engages the tack after the driver has inserted it in the shoe and last and 75 which is actuated to bend the tack during the cycle of the machine in which the tack is driven.

As herein shown, the tack bender is arranged for movement substantially parallel 80 to the surface of the work and the tack driver is arranged to insert a tack in the path of the tack bender. This construction insures the proper relative location of the tack bender and the driven tack for the 85 proper operation of the bender regardless of the spacing of successive tacks and constitutes another important feature of the invention.

In the construction herein shown by way 90 of example, the tack bender is mounted in the tack block for movement relatively thereto and mechanism operated by withdrawal of the tack driver acts to move the bender against the tack and bend it inwardly of the shoe.

Preferably the connection between the driver bar and tack bender is effective during withdrawal or upward movement of the driver bar, and the bender is restored to normal position by the rearward or return movement of the wiper. The effect of bending the tack inwardly of the shoe is to bring the upper part of the tack into a position more nearly perpendicular to the shoe bottom, thereby increasing the holding power of the tack by causing the upper to slip down the stem of the tack toward the sole. 105

instead of toward the head of the tack. Furthermore, the bending of the tack inwardly of the shoe increases the tension on the lasted upper.

5 These and other features of the invention will appear more fully from the following detailed description when read in connection with the accompanying drawing and will be pointed out in the appended claims.

10 In the drawing,

Figure 1 is a side view of the head of a hand method lasting machine equipped with my invention;

15 Fig. 2 is an enlarged side view of the mechanism embodying my invention and showing the position of the parts after descent of the driver;

20 Fig. 3 is a plan view, partly in section, of the tack block of the machine provided with my tack bending device;

25 Figs. 4 and 5 show, in perspective, views of the "thumb spring" with the tack bending device in its retracted and advanced positions respectively; and

30 Figs. 6 and 7 show the driven tack respectively before and after the tack is bent.

The machine to which the present invention is shown as applied is fully described in the Patent No. 597,321 above referred to and in United States Letters Patent No. 584,744, granted June 15, 1897, on application of Ladd & McFeely, to which patents reference may be had for explanation of parts not herein referred to.

35 The machine comprises (Fig. 1) a shoe rest 2 against which the shoe bottom is held at a considerable angle to the horizontal, particularly while the sides are being lasted, and has a gripper 4 which acts to seize 40 and tension the upper and to carry it over the shoe bottom. A tack block 6 then advances to wipe the upper over the edge of the shoe bottom, being mounted on a slide 8 which is reciprocated horizontally by connections to a cam 10. During its advancing movement the slide 8 engages the carrier 12 of the driver bar 14 and moves it forward in position to insert into the shoe the tack held by the tack block.

45 50 As shown in Fig. 2, the tack block 6 is secured to the slide 8 by screws 22. On the under side of the block 6 is a thumb spring piece 24, Fig. 4 which is secured to the slide 8 by the same screws 22 as the tack block. The tack block 6 is provided with the usual tack fingers 26, Fig. 3, to hold the tack in the tack block until it is driven by a driver 28, springs 30 being provided to hold the tack fingers 26 yieldingly pressed 55 60 toward each other to hold the tack.

65 A tack bender 40, Fig. 4, is mounted in a groove in the thumb spring 24 for movement in a substantially horizontal direction in line with the tack which is driven in front of it in a notch 42 in the thumb

spring. The tack bender is preferably provided with a notch 44 in its end to prevent movement of the tack laterally of the bender during its tack bending movement. The bender 40 is provided with an offset portion 70 46 having an ear 48 to which mechanism for operating it is connected.

This mechanism comprises an angle lever (Fig. 2) pivoted to the slide 8 at 50 and having an arm 52 pivotally connected to 75 the ear 48. Another arm 54 of the lever extends toward the driver bar and carries mechanism by which the arm 54 is uplifted during upward movement of the driver bar but is unaffected by downward movement of 80 the bar.

85 As shown, the arm 54 is bored longitudinally, and in the bore is mounted a stem 56 for longitudinal movement therein, being prevented from rotation by a pin 58 fixed in the stem 56 and extending through a slot 60 in the arm 54. The stem is held with the pin 58 at the forward end of the slot 60 by a spring 62 arranged between the angle lever and the stem 56. A dog 64 is 90 mounted on the forward end of the stem 56 by a screw 66 and interengaging teeth may be formed on the dog 64 and stem 56 to prevent relative movement of these parts and to permit adjustment of the dog about the 95 screw 66 when the screw is loosened. The dog 64 has a lower face 68 which, when the slide 8 is in advanced position, as shown in Fig. 2, is in line with a face 70 on the driver bar so that when the driver bar is raised 100 after its tack inserting movement these faces 68, 70 will engage and the angle lever will be moved about its pivot 50 and the tack bender 40 will be reciprocated forwardly to engage and bend inwardly of the shoe the 105 tack just driven by the driver.

110 When the slide 8 is retracted after the tack is driven and bent, an inclined face 74 on a rearward projection 76 of the angle lever will engage a corresponding face 78 110 on the machine frame, and the angle lever will be moved back to its normal position. Upon the next forward reciprocation of the slide 8, which occurs before the descent of the driver bar 14, the dog 64 will engage a 115 flat face 80 on the driver bar and will stop, continued movement of the slide compressing the spring 62. When the driver descends, the compressed spring 62 will force the dog 64 forwardly to bring its face 68 into line with the face 70 of the driver bar, as shown in Fig. 2, which faces will engage and effect forward movement of the bender 40 when the driver bar is raised after its tack driving movement. In its forward reciprocation the bender 40 passes between the tack fingers 26 and separates them against the pressure of the leaf springs 30, sufficient friction being thereby produced to prevent any movement of the bender and the angle 120 125 130

lever not produced by the operating mechanism as described. To facilitate the entrance of the forward end of the bender 40 between the tack fingers, it is beveled back- 5 wardly from the notch 44, as shown at 82 in Figs. 4 and 5. It will be observed that the arrangement of the dog 64, after adjustment on the end of the angle lever as described, affords means for varying the timing of the operation of the bender relatively to the movements of the driver bar.

Having fully described my invention, I claim as new and desire to secure by United States Letters Patent:

15 1. In a lasting machine, the combination with means for wiping successive portions of the upper into lasted position step by step, and means for driving tacks to secure the upper arranged to leave the tacks up- 20 standing above the surface of the work, of means operating independently of the wiping means to bend each tack inwardly of the shoe after it is driven.

2. In a lasting machine, the combination with means for wiping successive portions of the upper into lasted position, and means for driving tacks to secure the upper arranged to leave the tacks upstanding above the surface of the work, of means operated 30 by movement of the driving means after its driving movement for bending inwardly of the shoe the upstanding portions of the tacks.

3. In a machine for lasting portions of a 35 shoe upper successively, along the periphery of the shoe in repeated cycles, means for partially inserting a tack in each successive cycle, and means acting in the same cycle of the machine in which the tack is driven 40 to bend the tack inwardly of the shoe.

4. In a machine of the class described, the combination of means for working successive portions of a shoe upper over the shoe bottom, a driver, a driver bar for partially 45 inserting tacks to hold the upper in lasted position, a tack bender for bending inwardly of the shoe the upstanding portions of the tacks, and operative connections between the driver bar and the bender to operate the 50 bender.

5. A machine of the class described having, in combination, a reciprocating wiper constructed and arranged to wipe the upper over the last bottom, tacking mechanism 55 constructed and arranged partially to insert a tack to secure the upper while the upper is held over the last bottom, and additional means acting after the tack is driven and before the wiper is withdrawn 60 to bend the driven tack in a direction to increase its holding effect upon the upper.

6. A machine of the class described having, in combination, means for working an upper over a last into lasted position, a 65 tack driver for inserting tacks into the work

to hold the upper and to leave the upper portion of each tack upstanding above the shoe bottom, and means operated by withdrawal of the tack driver to bend the driven tack inwardly of the shoe.

7. A machine of the class described having, in combination, means for working an upper over a last into lasted position, a tack driver for inserting tacks into the work to hold the upper and to leave the head 70 end portion of each tack upstanding above the shoe bottom, means operated by withdrawal of the tack driver to bend the driven tack inwardly of the shoe, and means operated by retraction of the wiper for restoring the bending means to normal position.

8. In a machine of the class described, a tack driver, a wiper, a bender mounted in the wiper for movement toward and from a tack driven by the driver, and operating 85 means for the bender becoming effective when the driver is withdrawn for moving the bender against the driven tack to bend it inwardly of the shoe.

9. In a machine of the class described, a 90 tack driver, a wiper, a tack bender movable relatively to the wiper, means for operating the bender by movement of the driver in one direction, and separate means for moving the bender in the other direction.

10. In a machine of the class described, a tack block, a driver, means for advancing and retracting the tack block over the work, a tack bender movable relatively to the tack block to bend inwardly of the shoe the tack 100 driven by the driver, means operated by the driver to give the tack bender an operative movement, and means operated by the retraction of the wiper to give the tack bender an inoperative return movement.

11. A machine of the class described having, in combination, a movable tack block, a driver, and mechanism constructed and arranged to be operated by movement of the tack block and driver and acting to produce in the tack a bend which is initiated 110 at a point distant from the lower end of the tack.

12. A machine of the class described having, in combination, a driver, a movable tack block, mechanism for operating the driver and tack block, a tack bender, and means operated from said mechanism for moving the bender in a direction to bend the stem of the tack inwardly after the point of the 120 tack has entered the work and for restoring the bender to initial position after its tack bending movement.

13. In a machine of the class described, the combination of a tack bender movable 125 in a path substantially parallel with the surface of the work, and a tack driver arranged to insert a tack in the path of the bender.

14. In a machine of the class described,

the combination of a tack driver, a wiper movable over the shoe bottom, a tack bender movable with the wiper and in the path of a tack, driven in the same cycle, and means 5 for moving the bender farther than the wiper to bend the tack inwardly of the shoe.

15. In a machine of the class described, the combination of a tack bender movable 10 substantially parallel with the shoe bottom, a tack driver arranged to drive a tack in the path of movement of the bender, and means for operating the bender immediately after the tack is driven to bend the 15 tack inwardly of the shoe.

16. A machine of the class described having, in combination, a tack block carrier 20 movable inwardly of the shoe, a tack block mounted on the carrier provided with a passage for the driver, a driver bar movable at an oblique angle to the direction of movement of the tack block, a driver on the bar acting partially to insert a tack through the tack block at an oblique angle 25 to the face of the work, and means operated after each tack insertion to bend the up- standing portion of that tack into a position substantially perpendicular to the face of the work.

30 17. In a machine of the class described, a wiper carrier, a wiper, tack fingers mounted in the wiper, means for normally holding the fingers toward each other to retain the tack, a driver, a driver bar which is 35 advanced by the wiper carrier into position for its driver partially to insert a tack held by the tack fingers, a tack bender con-

structed and arranged to pass between the tack fingers to bend the upstanding portion of the tack away from the wiper, said 40 bender being actuated by connections to the driver bar which are operative only when the bar is withdrawn and being held from movement by the friction of the tack fingers when said connections are inoperative, 45 and means for restoring the bender to normal position after its tack bending movement.

18. A machine of the class described having, in combination, a combined tack block 50 and wiper, a driver bar having a driver for operating the tack block, a reciprocating tack bender mounted in the wiper, an angle lever having one arm connected with the bender, a dog mounted on the other arm of 55 the lever and arranged in the path of the driver bar whereby movement of the driver bar will actuate the angle lever and tack bender, and means permitting adjustment of the dog on the angle lever arm for timing 60 the movement of the bender relatively to the movement of the driver bar.

19. In a lasting machine, the combination with means for wiping successive portions 65 of the upper into lasted position, and means for driving tacks to secure the upper arranged to leave the tacks upstanding above the surface of the work, of additional means operated by movement of the driving means for bending inwardly of the shoe the up- 70 standing portions of the tacks.

In testimony whereof I have signed my name to this specification.

JOHN H. HAMILTON.
